UNITED STATES PATENT OFFICE.

ACHILLES DE KHOTINSKY, OF CHICAGO, ILLINOIS, ASSIGNOR TO CENTRAL SCIENTIFIC COMPANY, OF CHICAGO, ILLINOIS, A CORPORATION OF ILLINOIS.

PRECISION TEMPERATURE APPARATUS.

1,239,572.

Specification of Letters Patent. Patented Sept. 11, 1917.

Application filed December 9, 1916. Serial No. 136,102.

To all whom it may concern:

Be it known that I, ACHILLES DE KHOTINSKY, a citizen of the United States, residing at Chicago, in the county of Cook 5 and State of Illinois, have invented certain new and useful Improvements in Precision Temperature Apparatus, of which the following is a specification.

This invention relates in general to heat 10 interchanging apparatus and has for its primary object the provision in an electrically heated and thermostatically controlled water heater of means for controlling the flow of water through the heater in 15 a manner to insure efficiency of the heating elements, rapid responsiveness of the thermostat to temperature variations and uniformity of the temperature of the water delivered from the apparatus.

20 A further object of my invention is the provision of a method of and means for maintaining and delivering a medium at a predetermined temperature by inducing an internal circulation of the heated medium 25 whereby the medium is delivered at the mean temperature of the contents of the apparatus employed.

20 A further object of my invention is the provision in a water heater of means for preventing the accumulation of air released 30 from the water by heat and to insure that the internal pressure shall not exceed that of the atmosphere at any time.

Further objects and advantages of my invention will be apparent as it is better understood by reference to the following specification when read in connection with the accompanying drawing, illustrating the preferred embodiment thereof, in which—

40 Figure 1 is a vertical section through the apparatus;

Fig. 2 is a section on the line 2—2 of Fig. 1,

Fig. 3 is a similar section illustrating a 45 slightly different form of my invention and

Fig. 4 is a diagrammatic view of the electrical circuits.

Referring to the drawing, 1 indicates a casing of any suitable material divided by 50 a transverse partition 2 to provide chambers 3 and 4 which support the medium to be heated which in the embodiment herein described is water. An inlet pipe 5 is provided to continually deliver water to the

chamber 3 in which one or more electric 55 heating elements 6 are disposed. The heating elements 6 may be of any suitable construction but are preferably those disclosed in Patent No. 1,208,756, granted December 19, 1916, and are provided with inclosing 60 cylinders 7 which prevent access of the water to the heating elements. Surrounding the heating elements 6 is a pipe or conductor 8 arranged in a plurality of vertical loops. One end 9 of a pipe 8 is open to the 65 interior of the chamber 3 and is disposed adjacent the top thereof so that when water fills the chamber it will overflow and pass through the successive loops of the pipe to the chamber 4 in which the opposite end of 70 the pipe is disposed.

A thermostat 10 is disposed within the chamber 4 and may be of any suitable construction but is preferably that described in Patent No. 1,227,760, granted to me on May 75 29, 1917. The thermostat 10 is surrounded by a shell 11 and a pipe or conductor 12 open adjacent the top of the chamber 4 leads to the interior of the shell 11 so that when the water fills the chamber 4 it will overflow through the pipe 12 to the interior of 80 the shell. A pipe or conductor 13 leads from the interior of the shell 11 adjacent the top thereof to the delivery outlet 14 through which the heated water escapes. 85

The electric current fed to the heating elements 6 is controlled through any suitable intermediate mechanism such for example as the relay 15 diagrammatically shown in Fig. 4 in the circuit of the thermostat 10 90 and connected to a source of current supply by conductors 16 and 17. When the relay is energized by closure of the circuit through the thermostat 10 the circuits through the heating elements 6 will be broken and will 95 remain broken until the temperature of the water has fallen to a point below that at which the thermostat is adjusted to operate.

As will be readily understood the water which is delivered to the chamber 3 by the 100 pipe 5 is heated by contact with the walls of the cylinders 7 and by the interchange of heat due to convection currents in the body of the water. The more highly heated water rises to the upper part of the chamber 3 and 105 the temperature of the water gradually decreases toward the bottom. The hottest water overflows at 9 into the pipe 8 and

passes through the vertical loops, thus coming into direct contact, through the walls of the pipe, with the strata of varied temperature within the chamber. The result is an interchange of heat units between the water in the pipe 8 and the body of water in the chamber and because of the numerous loops in the pipe the water therein reaches, before its delivery to the chamber 4, the mean temperature of the body of water in the chamber 3. From the chamber 4 the water flows through the pipe 12 to the interior of the shell 11 where it surrounds the thermostat 10 which, being sensitive to slight variations in temperature, operates continually to modify the heat supplied to the chamber 3. The water then flows directly from the interior of the shell 11 to the outlet 14 through the pipe 13. It will be noted that each over-flow outlet is disposed adjacent the top of the chamber so that any air which may accumulate within the chamber can readily pass therefrom with the water. Consequently the chambers are always full of water during the operation of the apparatus and there can be no accumulation of pressure therein.

It may be desirable in order to obtain even greater accuracy in the temperature control to provide for internal circulation of the water in the chamber 4. Accordingly in Fig. 3 of the drawing I have illustrated the inlet pipe or conductor 12' arranged in a plurality of vertical loops to receive the water from the chamber 4 and convey it to the interior of the shell 11. The structure is otherwise identical with that previously described. In this form of my invention the heated water delivered to the chamber 4 eventually passes into the pipe 12' and is therein conducted through the vertical loops so that the water comes in contact through the walls of the pipe with the strata of different temperature in the chamber 4. Consequently the water delivered to the interior of the shell 11 is at the exact mean temperature of the body of water in the chamber 4.

With the embodiment of my invention herein described it is possible to maintain a continuous supply of hot water at a temperature which does not vary more than one one-thousandth of a degree centigrade. My invention is not, however, limited to a water heater since the broad idea of internal circulation to provide for heat interchange between a stream of the heated medium and successive strata in a surrounding body of the medium is applicable to a variety of media and purposes and I wish it understood that it is my intention to claim the subject-matter broadly as well as the specific application thereof herein described.

It will be apparent that various changes may be made in the form, construction and arrangement of the parts without departing

from the spirit and scope of the invention or sacrificing any of its material advantages, the form hereinbefore described being merely a preferred embodiment thereof.

I claim:

1. A method of maintaining and delivering a medium at a predetermined temperature comprising subjecting a body of the medium to heat sufficient to raise it to the desired temperature, continuously withdrawing a portion of the medium after causing it to repeatedly circulate vertically through said body, whereby heat is withdrawn from or given to succeeding strata and continuously adding a fresh supply of the medium to the body thereof. 70

2. In a heat interchanging apparatus, the combination of a container for the medium to be heated, means for applying heat to the latter, means for continuously supplying the medium to said container, and a conductor comprising a plurality of vertically arranged loops immersed in the medium and open at one end within said container to continuously withdraw the medium 85 from said container after subjecting it to the tempering influence of succeeding temperature strata. 90

3. In a heat interchanging apparatus, the combination of primary and secondary 95 chambers, electric heating means in said primary chamber, means for admitting the medium to be heated to said primary chamber, means for conveying said medium to said secondary chamber, a thermostat in 100 said secondary chamber for regulating the supply of current to said electric heating means, and means for delivering said medium from said secondary chamber. 105

4. In a heat interchanging apparatus, the combination of primary and secondary 110 chambers, electric heating means in said primary chamber, means for admitting the medium to be heated to said primary chamber, a conductor arranged in a plurality of vertical loops within said primary chamber and leading therefrom to said secondary chamber, a thermostat in said secondary chamber for regulating the supply of current to said electric heating means, and means for 115 delivering said medium from said secondary chamber. 120

5. In a heat interchanging apparatus, the combination of primary and secondary 125 chambers, electric heating means in said primary chamber, means for admitting the medium to be heated to said primary chamber, a conductor arranged in a plurality of vertical loops within said primary chamber and leading therefrom to said secondary chamber, a thermostat in said secondary chamber for regulating the supply of current to said electric heating means, a shell, surrounding said thermostat, means for conveying said medium from said secondary 130

chamber to the interior of said shell, and means for delivering said medium from the interior of said shell.

6. In a heat interchanging apparatus, 5 the combination of primary and secondary chambers, electric heating means in said primary chamber, means for admitting the medium to be heated to said primary chamber, a conductor arranged in a plurality of vertical loops within said primary chamber and leading to said secondary chamber, a thermostat in said secondary chamber for regulating the supply of current to said electric heating means, a shell surrounding said 10 thermostat, a conductor arranged in a plurality of vertical loops within said secondary chamber and leading to the interior of said shell, and means for delivering said medium from the interior of said shell.
- 20 7. In a water heater, the combination of a chamber, means for delivering water to said chamber, electric heating means in said chamber, a conductor arranged in a plurality of vertical loops within said chamber 25 and leading therefrom, the open end of said conductor within said chamber being disposed adjacent the top thereof to permit the escape of accumulated air.

8. In a water heater, the combination of 30 primary and secondary chambers, means for delivering water to said primary chamber, electric heating means in said primary chamber, a conductor arranged in a plurality of vertical loops within said chamber 35 and leading to said secondary chamber, the open end of said conductor within said primary chamber being disposed adjacent the top thereof to permit the escape of accumulated air, a thermostat in said secondary 40 chamber for regulating the supply of current to said electric heating means, and means for delivering water from said secondary chamber.

9. In a water heater, the combination of 45 primary and secondary chambers, means for delivering water to said primary chamber, electric heating means in said primary chamber, a conductor arranged in a plurality of vertical loops within said chamber and leading 50 to said secondary chamber, the open end of said conductor within said primary chamber being disposed adjacent the top thereof to permit the escape of accumulated air, a thermostat in said secondary chamber

for regulating the supply of current to said 55 electric heating means, a shell surrounding said thermostat, a conductor for delivering water from said secondary chamber to the interior of said shell, and means for delivering water from the interior of said shell. 60

10. In a water heater, the combination of primary and secondary chambers, means for delivering water to said primary chamber, electric heating means in said primary chamber, a conductor arranged in a plurality of 65 vertical loops within said chamber and leading to said secondary chamber, the open end of said conductor within said primary chamber being disposed adjacent the top thereof to permit the escape of accumulated air, a 70 thermostat in said secondary chamber for regulating the supply of current to said electric heating means, a shell surrounding said thermostat, a conductor for delivering water from said secondary chamber to the interior 75 of said shell, the open end of said conductor within said secondary chamber being disposed adjacent the top thereof to permit the escape of accumulated air, and a conductor leading from the top of said shell to deliver 80 water therefrom.

11. In a water heater, the combination of primary and secondary chambers, means for delivering water to said primary chamber, electric heating means in said primary chamber, a conductor arranged in a plurality of vertical loops within said chamber and leading to said secondary chamber, the open end of said conductor within said primary chamber being disposed adjacent the top thereof 85 to permit the escape of accumulated air, a thermostat in said secondary chamber for regulating the supply of current to said electric heating means, a shell surrounding said thermostat, a conductor arranged in a plurality of vertical loops within said secondary chamber for delivering water from said secondary chamber to the interior of said shell, the open end of said conductor within said secondary chamber being disposed adjacent the top thereof to permit the escape of accumulated air, and a conductor leading 90 from the top of said shell to deliver water therefrom. 95
